UNITED STATES PATENT OFFICE.

ALFRED HEALD, OF PHILADELPHIA, PENNSYLVANIA.

IMPROVEMENT IN LOOMS FOR WEAVING PILE FABRICS.

Specification forming part of Letters Patent No. 173,464, dated February 15, 1876; application filed April 19, 1875.

To all whom it may concern:

Be it known that I, ALFRED HEALD, of Philadelphia, Pennsylvania, have invented certain Improvements in Looms for Weaving Pile Fabrics, of which the following is a specification:

The object of my invention is to provide a loom for weaving pile fabrics, with a compact and efficient device for inserting and withdrawing the wires which form the pile; and this object I attain in the manner which I will now proceed to describe, reference being had to the accompanying drawing, in which—

Figure 1 is a side view of part of a loom for weaving pile fabrics with my improvement; Fig. 2, a section on the line 1 2, Fig. 1; Fig. 3, a section on the line 3 4; Fig. 4, a section on the line 5 6, drawn to an enlarged scale; and Figs. 5, 6, and 7, detached views of portions of my invention.

In ordinary looms for weaving pile fabrics the pile wires have been usually withdrawn by means of a traveling-frame, carrying a pair of nippers, and arranged at one side of the loom. This device is objectionable, on account of its complicated character and the amount of space occupied by it, a space necessarily as wide as that occupied by the loom itself.

I overcome these objections by the wire-operating mechanism illustrated in the accompanying drawing, in which—

A represents part of one of the side frames of the loom; and in a suitable bearing in this frame turns the driving-shaft *a*, carrying a number of scroll-cams, the duties of which will be explained hereafter. B is the cloth-roller, D the breast-beam, and E the lathe, the latter being reciprocated by scroll-cams *b* on the driving-shaft, through the medium of arms guided by and between flanged rollers *x*. (See Fig. 1.) In a bearing attached to the frame A turns one end of a longitudinal shaft, *d*, the opposite end of which is squared, and passes through the hub of a cog-wheel, *e*, (see Fig. 4,) adapted to a suitable bearing on the frame, so that the said shaft can slide freely in, but cannot turn independently of, the cog-wheel; to which motion is imparted by a rack, *f*, suitably guided in a bearing on the frame, and operated by a scroll-cam, *g*, in a manner and for a purpose explained hereafter. The

shaft *d* carries a curved arm, *F*, and is reciprocated longitudinally by a scroll-cam, *h*, Fig. 5, on the driving-shaft, through the medium of an arm, *G*, hung to a bracket, *i*, on the frame, and provided, at its lower end, with a clutch, *j*, which engages into a sleeve, *k*, keyed to the said shaft *d*, the form of the cam *h* being such that a comparatively long dwell is allowed between the reciprocating movements of the shaft.

In carrying out my invention, I propose to make the pile wires of steel, so tempered as to possess the required elasticity, and to admit of being readily bent over the curved arm *F*, the gripping of the wire being effected through the medium of spring-jaws *H*, Fig. 2, secured to the said arm, and the tendency of the spring being to close the jaws, which are opened at the proper intervals by the depression of a rod, *l*, which is acted upon by a finger, *m*, operated from a scroll-cam, *n*, on the driving-shaft through the medium of the lever *I*, the short arm of which is connected to an arm, *o*, attached to the shaft carrying said finger. The wire is adapted to a groove in the edge of the curved arm *F*; and the end of said wire when it is withdrawn from the fabric is prevented from flying upward by the bars *s s'*, (see Figs. 1 and 2,) which also serve to guide the wire during the movement of the arm *F*, and to deliver it properly into the open shed of the warp.

In order to insure the proper seizing of the ends of the wires by the gripping-jaws *H*, a spring-plate, *t*, Fig. 6, is arranged at the opposite end of the breast-beam from that at which the arm *F* operates, the spring-plate pressing on the ends of the wires, and causing them to project sufficiently to be readily seized by the jaws, the operation being also facilitated by raising the fabric slightly above the level of the breast-beam by means of a spring-plate, *t'*, secured to the said beam, as shown in Fig. 7.

The operation of the above-described mechanism is as follows: Supposing the parts to be in the position shown in Figs. 1, 2, and 4, a wire having just been inserted into the open shed of the fabric, the finger *m* will first be operated through the medium of the cam *n* and its connections, thereby depressing the

rod *l*, and opening the spring-jaws *H*, so as to release the wire just deposited in the shed. The shaft *d* and segmental arm *F* will then be moved forward to the position shown by dotted lines in Fig. 1, this movement being accomplished by the cam *h* through the medium of the arm *G*, clutch *j*, and sleeve *k*. The finger *m* and rod *l* are now relieved from pressure, and the spring-jaws *H* allowed to close upon the first wire *z* of the series, which has been pushed into the required position by the spring-plate *t*. The scroll-cam *g* now operates the rack *f* and cog-wheel *e*, so as to cause a partial revolution of the shaft *d* and the curved arm *F* in the direction of the arrow 1, Fig. 2, the wire being consequently withdrawn from the body of the fabric. The wire thus withdrawn is in the groove *p* of the curved arm, and its end is held between the bars *s* and *s'*, and is retained in its proper position during the reverse movement of the curved arm, which now takes place prior to the movement of the shaft *d* and the said arm *F* in the direction of the arrow 2, Fig. 2, so as to insert the wire in the new shed, which has just been formed, the previously-inserted wire having meanwhile been beaten up into the body of the fabric.

In order to counterbalance the weight of the arm *F*, I prefer to attach to the shaft *d* a quadrant, (shown in dotted lines in Fig. 1,) the weight of which is thrown on the opposite side of the shaft from that of said arm.

I claim as my invention—

1. In a loom for weaving pile fabrics, the curved arm or segment *F*, adapted, in connection with gripping, retaining, and releasing devices, to withdraw elastic wires from the fabric and insert them between the warp-threads, substantially in the manner described.

2. The combination of the segment-arm *F* with spring-jaws *H* and mechanism, substantially as described, for operating the jaws at intervals.

3. The combination of the gripping-jaws *H* on the segment-arm *F* with the guiding and retaining bars *s* *s'*.

4. The combination of the gripping-jaws *H* and operating mechanism, substantially as described, with the spring-plates *t* and *t'*.

5. The combination of the pile-wire inserting and withdrawing arm with the square rock-shaft *d*, cog-wheel *e*, rack *f*, and cam *g*, the shaft *d* being adapted to slide in the wheel *e*, as set forth.

6. The combination of the pile-wire inserting and withdrawing arm with the sliding shaft *d*, cam *h*, arm *G*, clutch *j*, and sleeve *k*, all substantially as set forth.

In testimony whereof I have signed my name to this specification in the presence of two subscribing witnesses.

ALFRED HEALD.
